Attorney.

UNITED STATES PATENT OFFICE.

BENJAMIN JAMES HALL, OF FIELDEND, EASTCOTE, AND CARL FREDERIK GRIMUR THORKELIN, OF LONDON, ENGLAND.

ARC LAMP FOR PHOTOGRAPHIC AND OTHER PURPOSES.

Application filed April 1, 1920. Serial No. 370,467.

To all whom it may concern:

Be it known that we, BENJAMIN JAMES HALL, subject of the King of Great Britain, residing at Fieldend, Eastcote, in the county of Middlesex, England, and CARL FREDERIK GRIMUR THORKELIN, subject of the King of Denmark, residing at 3 Wolseley Road, Crouch End, London, N. 8, England, have invented new and useful Improvements in

10 Arc Lamps for Photographic and Other Purposes, of which the following is a specification.

This invention has reference to arc lamps of the enclosed type in which the arc is placed horizontally, the lamp being suitable for emitting the light from the arc in a downward direction, and also for burning with a long arc suitable for photographic purposes.

20 According to this invention we place the carbons converging in a wide angle to each other with their lower ends passing through and into an arc enclosing chamber, where the points of the carbons meet. The upper 25 part of this chamber is opaque and the lower part translucent.

Each carbon holder is pivoted on the lower end of an arm capable of swinging in the direction in which the carbons move 30 for striking and maintaining the arc. These arms are pivoted or hinged and may be extended upwards beyond the point at which they are pivoted somewhat similar to a pair of scissors either open or crossed. Or the 35 arms may terminate at the pivot or pivots thus resembling a hinge.

The arc is controlled, preferably, by a solenoid the iron core of which is suspended from the swinging arms by flexible connections passing over pulleys.

The arc is further controlled by a blow magnet in proximity thereto in the usual known manner.

The invention is illustrated on the accompanying drawings.

Fig. 1 is a diagrammatical view showing our method of supporting the carbon holders and moving the carbons for striking and maintaining the arc.

Fig. 2 is a similar view showing a slightly modified form of our invention.

A represents the carbon holders, B the carbons, D the arc enclosing chamber into which the lower ends of the carbons pass, E the swinging arms to which the carbon 55 holders are pivoted, and F the iron core of the solenoid H. The chamber D has holes in its sides which form guides for the pivoted carbons to slide in.

In the method shown by Fig. 1 the swinging arms E extend upwards beyond the point e' at which they are pivoted, the iron core being suspended from these extended portions by the flexible connections e² passing over the pulleys e³.

At Fig. 2 we have shown the swinging arms E terminating at the pivot point e'. In this case the flexible connections e² are attached to the arms preferably below the pivot point e' each flexible connection, by 70 which the core F is suspended, passing preferably, over two pulleys e³, e⁴. Or the flexible connections may be carried to the solenoid core in any manner that will enable the carbons to move in accordance with the 75 movement of said core.

In order that the lamp may give powerful actinic rays for photographic purposes, the carbons are arranged at a wide angle, of substantially 130 degrees. The carbons are 80 arranged to work with a long arc, being widely separated, and provided with current of suitable voltage.

As the carbons burn away each arm E is moved pivotally to an equal extent by the 85 single solenoid so that the arc is maintained substantially central of the translucent bottom portion of the inclosing chamber D.

What we claim as our invention and desire to secure by Letters Patent is:—

An arc lamp for photographic purposes, comprising a chamber having a translucent bottom and guide holes in its upper part, two arms supported pivotally above the said chamber, carbons arranged at substantially 95 an angle of 130 degrees, the upper parts of the carbons being pivoted to the lower parts of the said arms and the lower parts of the

carbons being slidable in the said guide holes, a solenoid included in circuit with the carbons and provided with a slideable core, guide sheaves, and flexible connections passing over the guide sheaves and attached to the said arms and to the solenoid core so that the weight of the said core assists in moving the carbons apart.

In testimony whereof we have signed our names to this specification in the presence 10 of two subscribing witnesses.

BENJAMIN JAMES HALL.

CARL FREDERIK GRIMUR THORKELIN.
